A. M. Crow.

ATTORNEY.

UNITED STATES PATENT OFFICE.

ALFONZO M. CROW, OF METAMORA, ILLINOIS.

EGG CASE.

Application filed April 19, 1920. Serial No. 375,144.

To all whom it may concern:

Be it known that I, ALFONZO M. CROW, a citizen of the United States, residing at Metamora, in the county of Woodford and 5 State of Illinois, have invented certain new and useful Improvements in an Egg Case; and I do hereby declare the following to be a full, clear, and exact description of the invention, such as will enable others skilled 10 in the art to which it appertains to make and use the same.

The object of the invention is to provide a simple and relatively inexpensive and durable receptacle for shipping eggs and 15 other products from the farmer or producer to the market and for shipping eggs and other farm products by merchants and others wherein the disadvantages of the use of wooden crates in the fact that they 20 are readily injured or destroyed and occupy an unnecessary amount of space due to the thickness of the walls thereof, are avoided, and with this object in view the invention consists in a construction and combination 25 of parts of which a preferred embodiment is shown in the drawing, wherein;

Figure 1 is a perspective view of a case embodying the invention.

Figure 2 is a longitudinal sectional view 30 of the same.

Figure 3 is a horizontal sectional view on the plane indicated by the line 3—3 of Figure 2.

Figure 4 is a plan view of the blank 35 from which the body portion of the case is formed.

Figure 5 is a similar view of the blank forming the intermediate partition.

The crate consists essentially of the bottom 40 with the side walls 11 and end walls 12, represented respectively by integral folds of sheet metal, as indicated in Figure 4, the end folds being provided with terminal flaps 13 for overlapping relation and attachment 45 to the exterior surfaces of the side wall folds to reinforce the latter and produce continuous corner joints to avoid breaking down or the distortion of the receptacle when subjected to the rough usage incident 50 to transportation. The upper edges of the end wall folds are curled or beaded outwardly as shown at 14 to produce eyes spaced apart at their inner ends for the reception of a corresponding eye 15 formed 55 by a coiled or rolled tongue at each ex-

tremity of the cover fold or blank 16, and the registering eyes are engaged by hinge pins 17, either of which may be withdrawn to permit of the opening of the case. Arranged transversely in the case is a partition 18 formed of a blank shown in Figure 5, having the terminal longitudinal flaps 19 adapted for arrangement in contact with and attachment by solder or the equivalent thereof to the inner surfaces of the side 60 walls of the case in overlapping relation with the exterior reinforcing flaps 13, and also provided with an intermediate side flap 20 which is adapted to be folded and arranged in contact with the inner surface of 70 the bottom fold of the case to which it may be secured by solder or the equivalent thereof.

When the article is set up as shown in Figures 1, 2 and 3 it is of a rigid construction adapted to perform all of the functions of the usual crate and at the same time withstand the rough usage to which such devices are subjected, without the possibility of distortion which causes the 80 injury of the contents, particularly when eggs or like articles are transported therein, and are disposed in the usual egg cells with which the compartments of the case may be provided as in the ordinary practice.

Moreover the lid or cover is permanently and substantially attached at its extremities to the upper edges of the end walls of the case and remain permanently connected 90 therewith in a movable relation thereto, but may be released at either end to give access to the interior for the removal of the contents, and when the cover is secured the means of fastening the same, consisting as 95 described of the registering eyes and the engaging hinge pins lend themselves readily to the application of sealing means to prevent the surreptitious opening of the case without detection upon the part of the 100 consignee.

The case is to be made in the standard sizes for holding thirty-dozen or more eggs. It is also to be made in half and other smaller sizes. It is indestructible and in 105 view thereof and as it protects the contents from spilling, wasting and spoiling while in transit the shipper, the carrier and the consignee will not have to meet claims for loss and damage to the products.

Having thus described my invention, what I claim is:

In a case, a partition to provide compartments on each side thereof consisting of a blank having a partition portion, end flaps extending from said portion in opposite directions and engaging spaced walls of the case, and a flap extending from one longitudinal edge of the partition portion

and engaging a wall of the case in spanning 10 relation to the first mentioned walls.

In testimony whereof I affix my signature in presence of two witnesses.

ALFONZO M. CROW.
